BATHING FIXTURE

Arthur P. Woolfolk, Pittsburgh, Pa., assignor to
Standard Sanitary Manufacturing Company, a
corporation of New Jersey

Application June 4, 1932, Serial No. 615,404

7 Claims. (Cl. 4—173)

This invention relates to fixtures for use in bathrooms and more particularly to a bathing fixture which provides a combined full length immersion tub and shower receptor, and is a 5 continuation in part of my pending application Serial No. 608,671, filed May 2, 1932.

The general plan in installing bathrooms in apartment houses and small homes is to place the bathtub in a corner of the room or in a 10 recess formed in one of the walls so that at least two or three sides of the tub are enclosed. A shower head is provided which extends from one of the walls enclosing the tub and the tub itself forms the shower receptor. The tubs now 15 generally used as shower receptors are relatively narrow in width and have a sloped bottom. The water from the shower is prevented from splashing over the floor by a curtain suspended from a rod mounted above the exposed sides of 20 the tub. Such an arrangement is unsatisfactory as a shower bath because the tub being so narrow does not give the bather sufficient room to turn while standing in the tub and the sloped bottom of the tub forms a serious hazard to the 25 bather since there is always present the possibility that the bather will slip on the wet enamel of the bottom and be seriously injured by falling against the edge of the tub.

Also, the relatively narrow tubs are objectionable as shower receptors because the jets of water issuing from the shower head are sprayed over the sides of the tub and strike the shower curtain from which it drips onto the floor of the 30 bathroom.

35 An object of this invention is to provide a bathing fixture arranged and constructed to form an immersion tub and also a relatively wide shower receptor.

Another object of this invention is to provide 40 a bathing fixture having a tub cavity provided with a relatively wide, flat bottomed central portion which forms a shower receptor.

Another object of this invention is to provide 45 a bathing fixture having seats formed at the corners thereof adjacent the cavity to enable the bather to sit down while taking a shower bath.

These and other objects which will be made 50 apparent to those skilled in this particular art are accomplished by means of this invention, one embodiment of which is described in the following specification and illustrated in the accompanying drawings, wherein:

Figure 1 is a view in perspective of my improved bathing fixture.

55 Fig. 2 is a top plan view of my improved fixture.

Fig. 3 is a view in vertical section taken on line III—III of Figure 2.

Fig. 4 is a view in vertical section taken on 60 line IV—IV of Figure 2.

Fig. 5 is a perspective view of a bathing fixture embodying a modification of my invention.

Fig. 6 is a top plan view of the fixture illustrated in Figure 5.

Fig. 7 is a view in vertical section taken on 65 line VII—VII of Figures 6 and 7; and

Fig. 8 is a view in vertical section taken on line VIII—VIII of Figure 6.

Referring to the drawings in detail, my improved bathing fixture, designated in its entirety as 10, is shown as installed in a recess of a room so that three sides thereof are enclosed by walls 11 forming the recess. My improved fixture 10 which is substantially rectangular in shape and is of substantially the same length as 75 the ordinary standard bathtub now in general use, has a cavity formed therein of the usual depth extending longitudinally of the fixture which forms a combined immersion tub and shower receptor. So that the cavity will be of 80 sufficient width to receive within its confines all the sprays of water issuing from a shower head 12, extending from one of the walls 11, I form an offset in one of the walls of the cavity whereby a relatively wide portion is provided in the 85 center thereof. The tub cavity in my improved bathing fixture has a relatively flat bottom 13 and a straight side wall 14 along one of the sides thereof, illustrated in Figs. 1 to 4, inclusive, as being along the side of the fixture which is adapted to be open or exposed, which terminates at each end of the cavity in end walls 15 and 16.

In order to form the offset in the wall parallel to the wall 14 to increase the width of the 95 tub cavity and provide a substantially square central portion in the fixture suitable for use as a shower receptor, the end walls 15 and 16 which are of substantially the same length as the end walls of the ordinary bathtub terminate in walls 100 17 and 18, respectively, arranged diagonally to the longitudinal axis of the fixture instead of in the ordinary side wall. These walls 17 and 18 in turn terminate in a wall 19 substantially parallel to the wall 14 and form an offset wall providing a relatively wide substantially square, 105 central portion in the cavity, having a substantially flat floor or bottom.

These side walls of the cavity terminate at the top in a flat rim 20 which extends around the 110 top of the fixture. The rim 20 adjacent the diagonal walls 17 and 18 is triangular in shape and forms seat portions 21 and 22 on the corners of the fixture along the side thereof adapted to abut against the wall 11 and permit the 115 bather to sit down while taking a shower bath. These seats also permit the fixture to be used as a footbath as well as for immersion and shower baths.

The straight side wall 14 of the tub cavity 120

may be covered by an apron 23 depending from the rim 20 as shown in the drawings, or the apron wall may be left off if desired, and the front wall of the fixture tiled in as is customary 5 in installing certain types of bathtubs.

As a result of my improved construction and arrangement of the parts of the tub, I am able to make the bottom 13 of the tub considerably flatter than has been possible heretofore, and 10 to install the outlet designated as 24 in the center of the cavity instead of at the end as has heretofore been the customary practice.

In Figs. 5, 6, 7, and 8 I have illustrated a modified form of my invention in which the wall of 15 the cavity facing into the room, that is, the exposed walls of the cavity is offset to provide the relatively wide substantially square central portion in the tub cavity instead of the wall which is adapted to abut against the walls of the room 20 as heretofore described. In this modification a fixture 10' adapted to be received in a corner formed by walls 11', one of which has a shower head 12' extending therefrom, is provided with a tub cavity, the bottom 13' of which is substantially flat.

Formed integral with the bottom along the side of the cavity which is adapted to be disposed next to the wall 11' is a straight side wall 14' which terminates at each end of the fixture 30 in walls 15' and 16'. The walls 15' and 16' are so formed that they do not fully extend across the ends of the fixture and they in turn terminate in diagonally extending walls 17' and 18' which are connected together by a side wall 19'. The walls 17', 18', and 19' form an offset wall 35 on one side of the tub cavity of the fixture 10' which materially increases the width of the cavity in the central portion of the fixture 10' and provides a substantially square portion suitable for use as a shower receptor.

The walls bounding the tub cavity terminate at the top of the fixture in a flat rim 20' which extends around the upper edge thereof. The 45 portions of the rim 20' adjacent the diagonally extending walls 17' and 18' are triangular in shape and form seats 21' and 22', respectively, at the corners of the fixture along the exposed side thereof.

The offset wall of the fixture may be covered 50 by an apron 23' depending from the rim 20' or, as in the previously described modification, may be tiled in.

The water is drained from the tub cavity through a suitable outlet opening 24' connected 55 to a drain (not shown).

From the foregoing description it is apparent that either wall of the tub cavity in the fixture may be offset to increase the width of the central portion thereof and provide the substantially square central portion in the fixture. It is also apparent that such a fixture is capable of being used as a shower receptor as well as an 60 immersion tub. In the last described modification, the seats being adjacent the exposed or open side of the tub, enables the bather to sit down when entering the tube and eliminate to a great extent the danger of slipping and falling when getting into and out of the tub. It is also apparent that the drain outlet may be placed at 65 one end of the tub cavity or in the center thereof, as desired.

While I have disclosed one embodiment of my invention it is readily apparent that certain changes or modifications may be made therein without departing from the spirit of my invention or the scope of the appended claims.

What I claim as new and desire to secure by Letters Patent is:

1. A bathing fixture comprising a body having a bottom, a relatively long side wall, a relatively short side wall, end walls extending at right angles to said relatively long wall and diagonal walls connecting said end walls with the relatively short side walls.

2. A bathing fixture having a tub cavity therein, the side walls of which are parallel to each other but of different lengths and connected together at each end by two walls one of which extends transversely of the fixture and the other diagonally of the longitudinal axis thereof thereby providing a relatively wide middle portion in said cavity, and seats at the corners of said fixture adjacent said diagonal walls.

3. A bathing fixture comprising a rectangular body having a bottom, parallel side walls extending upwardly from the bottom, one of said side walls being longer than the other, diagonally extending walls at each end of the shorter side wall and transversely extending end walls connecting the ends of said diagonal walls with the ends of the longer of said side walls where- 105 by a middle portion substantially wider than the end portions and suitable for use as a shower receptor is provided in said fixture.

4. A bathing fixture having a tub cavity there- 110 in, each end of which is defined by two walls, one wall being transverse to the longitudinal axis of said fixture and the other extending diagonally of the longitudinal axis of the fixture to provide a relatively wide middle portion in said cavity, and seats on the corners of said fixture adjacent the top of the diagonal walls thereof.

5. A bathing fixture comprising a body having a bottom, a side wall extending upwardly from one side of the bottom, end walls connected to 120 the ends of said side walls, walls extending diagonally from the end walls, and a wall parallel to but of shorter length than said first-mentioned side wall connecting the ends of said diagonally extending walls.

6. A bathing fixture of the character described having a relatively flat bottom, a side wall extending upwardly from one side of said bottom, a transversely extending end wall at each end of said bottom and joined to said side 130 wall, a wall connected to each of said end walls and extending diagonally to the longitudinal axis of said fixture, a wall parallel to said side wall connecting said diagonal walls, said bottom and walls forming a tub cavity having a relatively wide middle portion and seats formed on said fixture at the top of the diagonal walls.

7. An improved bathing fixture comprising a rectangular body having a longitudinally ex- 140 tendsing tub cavity therein, the middle portion of which is substantially wider than the extreme end portions and the width of the cavity gradually increases from the extreme ends to the middle portion thereof.

ARTHUR P. WOOLFOLK. 145
